UNITED STATES PATENT OFFICE.

LOUIS A. BRENER, OF SANDWICH, ILLINOIS.

MECHANICAL MOVEMENT FOR CONVERTING MOTION.

SPECIFICATION forming part of Letters Patent No. 425,534, dated April 15, 1890.

Application filed December 26, 1889. Serial No. 334,973. (No model.)

To all whom it may concern:

Be it known that I, LOUIS A. BRENER, a citizen of the United States, residing at Sandwich, in the county of De Kalb and State of Illinois, have invented certain new and useful Improvements in Mechanical Movements for Converting Motion; and I do declare the following to be a full, clear, and exact description of the invention, such as will enable others skilled in the art to which it appertains to make and use the same, reference being had to the accompanying drawings, and to the letters of reference marked thereon, which form a part of this specification.

The special object of the invention is to produce a mechanical movement by which the reciprocating pump-rod of a windmill may impart rotary motion for driving other machines.

The invention will first be described in connection with the drawings, and then pointed out in the claim.

Figure 1 of the drawings is an elevation in perspective; Fig. 2, a plan view, partly in section; and Fig. 3, a detail perspective view of the coil-spring with the pivoted spring-pawl upon its end.

In the drawings, A represents a vertical plate having cogs on each of its opposite edges and provided with the arms $a a' a''$. The arm a passes through the guide a^2 in the upright frame J and connects with the pump-rod of a windmill, which moves it up and down. On the lower end of the rack-plate the arms $a' a''$ pass through the frame-guides $a^3 a^3$.

C C are two pinions keyed to the ends of the shafts D D and rotating them as they turn. The shafts D D are journaled in and extend across the frame J, so that the pinions C C may be rotated by the rack-plate A. On each of the shafts D is made fast one end of a heavy coil-spring F, whose free end extends

out a little beyond the outer edge of the ratchet-wheel E', which is fast concentrically upon the side of the spur-wheel E. This spring F 45 has on its end a carrying-pawl f, which is held to the ratchet by a small spring f'.

To the rotary shaft G, journaled in and extending across the frame J, is keyed a pinion H, which meshes with both of the oppositely-placed spur-wheels E E. On the same shaft G is also made fast a balance-wheel I.

The operation is as follows: The reciprocating rack-plate A oscillates the wheels C C, which actuate the shafts D D, while the pawls f alternately carry the spur-wheels E a half-revolution, one as the rack-plate moves up and the other as the rack-plate moves down, thus causing the pinion H to revolve continuously with the shaft G and balance-wheel I. 60 At the start and termination of the up and down strokes of the rack-plate A there is a sudden momentary stop and start, which tends to give an unsteady motion to the windmill; but I prevent this by the use of the springs F 6 and the balance-wheel I.

Having thus described all that is necessary to a full understanding of my invention, what I claim as new, and desire to protect by Letters Patent, is—

The combination, with the reciprocating rack-plate A, the shafts D D, carrying pinions C C, the shaft G, carrying the pinion H, and the spur-wheels E E, carrying the ratchet-wheels E' E', of the springs F F, coiled about 75 the shafts D, having one end attached thereto, and provided at the other end with the spring-pawls f f, as and for the purpose set forth.

In testimony whereof I affix my signature in presence of two witnesses.

LOUIS A. BRENER.

Witnesses:

O. K. LEMERE,
AUGUST BRENER

It is hereby certified that the name of the patentee in Letters Patent No. 425,534, granted April 15, 1890, for an improvement in "Mechanical Movements for Converting Motion," was erroneously written and printed "Louis A. Brener," whereas said name should have been written and printed *Louis A. Breuer*; and that the said Letters Patent should be read with this correction therein that the same may conform to the record of the case in the Patent Office.

Signed, countersigned, and sealed this 13th day of May, A. D. 1890.

[SEAL.]

CYRUS BUSSEY,
Assistant Secretary of the Interior.

Countersigned:

C. E. MITCHELL,
Commissioner of Patents.
